UNITED STATES PATENT OFFICE.

CARL B. DREVITSON, OF SOMERVILLE, MASSACHUSETTS.

SKATE.

1,405,981.

Specification of Letters Patent.

Patented Feb. 7, 1922.

Application filed February 15, 1921. Serial No. 445,144.

To all whom it may concern:

Be it known that I, CARL B. DREVITSON, a citizen of the United States, residing at Somerville, in the county of Middlesex and State 5 of Massachusetts, have invented new and useful Improvements in Skates, of which the following is a specification.

This invention relates to a skate of the type disclosed by my Patent No. 1,115,790, 10 of November 3, 1914, including a runner, and a cast-metal foot-supporting frame united to the runner, and composed of a metal different from that of the runner, the frame being usually cast from a metallic 15 mixture containing aluminum, while the runner is usually composed of steel.

Heretofore the frame has been cast in one piece. In the skate shown by my former patent the frame is united with the runner 20 by being cast directly thereon, the frame being interlocked with the runner by the casting operation. Owing to the somewhat complex form of the frame the casting operation sometimes results in the formation of imperfect castings, involving loss of time, labor 25 and material.

The present invention has for its object 30 to prevent liability of such loss, and is embodied in a skate, the frame of which is cast in two separate sections, united to each other and to the runner after the casting operation, the assemblage of said sections and the runner forming a skate of the same general form and appearance as that of my former 35 patent.

Of the accompanying drawings forming a part of this specification,—

Figure 1 is a side elevation of a skate embodying the invention.

Figure 2 is a top plan view of the same.

Figure 3 is a section on line 3—3 of Figure 1.

Figure 4 is a section on line 4—4 of Figure 1.

Figure 5 is a section on line 5—5 of Figure 1.

Figure 6 is a perspective view of one of the frame sections.

The same reference characters indicate the 50 same parts in all of the figures.

In the drawings, 12 represents the runner, which may be of any desired form.

The cast-metal foot-supporting frame is composed of two independently cast sections 55 forming, when assembled, an elongated base 13, 13^a, recessed to receive the upper

edge of the runner, spaced apart standards, of which three are here shown, projecting upward from the base, there being a rear standard designated by 14, 14^a, a front standard designated by 15, 15^a, and an intermediate standard designated by 16, 16^a, a heel support, designated by 17, 17^a at the upper end of the rear standard, and a sole support designated by 18, 18^a at the upper ends of 60 the front and intermediate standards. The rear and intermediate standards are usually hollow and of tapering form.

The sectional construction of the frame is disclosed in the completed skate by a longitudinal seam or joint at the median line of 70 the frame, as indicated by Figures 2, 3, 4 and 5.

Each section is provided with a downwardly facing longitudinal shoulder 19 on 75 its base portion, bearing on the upper edge of the runner, a side face 20 above said shoulder, the side faces 20 of the two sections being reciprocal and abutting against each other, and lower side faces 21 below 80 the shoulders 19 bearing on the opposite sides of the runner.

Each reciprocal side face 20 is extended or ramified, as best shown by Figure 6, so that it includes portions formed on the base, the 85 standards and the heel and sole supports.

It will be seen that the form of the sections is relatively simple, so that liability of forming imperfect castings is reduced to a minimum.

When the sections are assembled on the runner they are united to the runner and to each other. The base sections 13, 13^a are united to each other and to the upper portion of the runner by rivets 23, and the 95 standard sections are united to each other by rivets 24, engaged with ears 25, formed on said sections, the meeting faces of the ears being flush with the side faces 20.

The bearing of the downwardly facing 100 shoulders 19 of the base sections on the upper edge of the runner 12, prevents shearing pressure on the rivets 23 and 24, by the pressure of the wearer's foot on the sectional heel and sole supports.

I claim:

1. A skate comprising a runner and a cast-metal foot-supporting frame, composed of independent sections forming, when assembled, an elongated sectional base recessed to receive the upper edge of the runner, spaced apart sectional standards pro-

jecting upward from the base, sectional heel and sole supports at the upper ends of said standards, said sections being provided with downwardly facing longitudinally extending shoulders, bearing on the upper edge of the runner, upper reciprocal side faces above said shoulders, said side faces abutting against each other 30 and including portions formed on the base, the standards, 10 and the heel and sole supports, and lower side faces below said shoulders bearing on opposite sides of the runner, rivets uniting the base sections to the runner, and rivets uniting the standard sections to each other, 15 the bearing of said downwardly facing shoulders on the upper edge of the runner preventing shearing pressure on said rivets.

2. A skate comprising a runner and a cast-metal foot-supporting frame, composed 20 of independent sections forming, when assembled, an elongated base recessed to receive the upper edge of the runner, spaced apart standards projecting upward from the base, and heel and sole supports at the 25 upper ends of said standards, said sections

being provided with downwardly facing longitudinally extending shoulders, bearing on the upper edge of the runner, upper reciprocal side faces above said shoulders, said side faces abutting against each other 30 and including portions formed on the base, the standards, and the heel and sole supports, and lower side faces below said shoulders bearing on opposite sides of the runner, the base portions of the sections 35 being united to each other and to the runner, and the standard portions being provided with reciprocal ears flush with said side faces, and united to each other above the runner by rivets.

3. A skate substantially as specified by claim 1, the base portions of the sections being united to each other and to the runner, and the standard portions being provided with reciprocal ears flush with said 50 side faces, and united to each other above the runner by rivets.

In testimony whereof I have affixed my signature.

CARL B. DREVITSON.
